UNITED STATES PATENT OFFICE.

JOHN J. COMER, OF CHICAGO, ILLINOIS, ASSIGNOR TO AUTOMATIC ENUNCIATOR COMPANY, OF CHICAGO, ILLINOIS, A CORPORATION OF ILLINOIS.

TRANSMITTING APPARATUS.

1,209,397.

Specification of Letters Patent. Patented Dec. 19, 1916.

Application filed February 24, 1914. Serial No. 820,692.

To all whom it may concern:

Be it known that I, JOHN J. COMER, a citizen of the United States of America, and resident of Chicago, Cook county, Illinois, 5 have invented a certain new and useful Improvement in Transmitting Apparatus, of which the following is a specification.

My invention relates to transmitting apparatus which is particularly adapted for 10 use in connection with loud speaking systems. It is also especially adapted for transmitting voices or sounds in chorus from other sources.

In my invention I make use of the general 15 Wheatstone bridge principle and in transmitters of this kind it is the usual custom to employ a single source of energy in the system unless induction coils are used. It is my plan to use a separate source of current 20 with each transmitter center. As far as I know it has been impractical heretofore to bank transmitters so as to get an accumulation 25 of voltage due to their variations. Transmitters have been sometimes connected, a great number in multiple, and sometimes a great number in series, but the result has always been unsatisfactory. Where 30 the transmitters are connected in multiple there is no increase in voltage although there is an increase in volume. Where the transmitters are connected in series it is found 35 that the greater the number in series the worse the transmission. In fact, it may be said that a single transmitter gives better results than a lot of transmitters in series.

Generally stated, the object of my invention 40 is to provide a highly efficient transmitter system in which different centers or combination of centers may be used for a single source of sound, and these centers or combination of centers can be brought together for the purpose of blending all of the sounds in a common circuit.

The means for accomplishing the foregoing 45 and other useful ends are hereinafter set forth and claimed.

Referring to the drawing, Figure 1 shows 50 a series of transmission centers or units associated with a single line. Fig. 2 is a modification of the same. Fig. 3 shows a line provided with a series of reproducers of any suitable type as, for example, the type shown in British Patent 21892 of 1911. Fig. 4 is an adaptation of my apparatus to wire-

less telephony. Fig. 5 shows a plurality of 55 units in a main circuit and divided into groups.

Referring to Fig. 1, it will be seen that one transmission center comprises battery B, and differential microphone 2 divided into 60 two sections 3 and 4 by the central diaphragm 5. The same center also comprises two branches, one containing the resistance 6 and the other the resistance 7. The second one of the centers contains the differential 65 microphone 8 and two branches, one containing the resistance 9 and the other the resistance 10. This center is supplied by the battery B'. It will be observed that these two centers which are supplied by the battery B and B', have a side 11 in common. The third center comprises the transmitter 12, battery B² and the resistances 13 and 14. This third center has a side 15 in common with the center containing battery B'. All 70 of these centers, it will be seen, are connected with a line 16. Now any sound which will affect the central member 5, for example of the center containing the battery B, will cause the diaphragm 5 to vary the resistance in 75 the sides 3 and 4. By this varying resistance a variation of potential originating in the battery B is made to occur in the line 16. The same is true in regard to each of the other centers with regard to its own battery. 80 Obviously, therefore, if a separate source of sound is made to affect each of the microphones 2, 8 and 12 separately in the line 16, there will occur a variation of potential 85 which will be resultant of all of the variations. There is no limit to the number of centers which can be connected up in this manner and whenever it is necessary or desirable, one source of sound can be caused to affect one or more of the centers, and another source of sound can be caused to affect 90 one or more additional centers.

In my invention it is feasible to combine any number of centers to obtain on the line which is common to them all an algebraic 100 result of all the voltages due to the variations of potential in the centers.

Referring to Fig. 2, it will be seen that it is the same as Fig. 1, with the exception that in the place of the center controlled by 105 the battery B² a differential microphone 17 has been substituted for resistances, such as the resistances 6 and 7 in the center con-

trolled by the battery B. A similar change has been made in each of the other centers controlled by the batteries B⁴ and B⁵.

Either of the circuits shown in Fig. 1 and Fig. 2 may be connected to the amplified circuit shown in Fig. 3, that is, line 16 may be connected to the line 18 or the line 19 may be connected to the line 18. Similarly either of the lines 16 or 19 can be connected to the line 20 in Fig. 4 for wireless transmission. In this Fig. 4 there is shown at 21 an arc light and associated with this arc light a source of energy at 22. In series with this source of energy there is the secondary 15 winding 23 of the induction coil, the primary 24 of which is connected with the transmitter circuit, as already explained. The arc light 21 is shunted by the condenser 25 and inductance 26. In series with this 20 condenser and inductance is a primary winding 27 for affecting the aerial 28.

Fig. 5 shows the main line having conductors 31 and 32 terminating in an instrument 36, which may be a repeater or wire- 25 less apparatus. It shows a plurality of units C, D, E, F, G, H, divided into groups, such as C D, E F, and G H, and a source of sound for each group indicated at I, J, K, which sources may be of any kind. It 30 will be seen, therefore, that when the diaphragm, such as the diaphragm 5, is normal, that is, when it is adjusted so that the ratio of the resistances in the arms stand so that resistance 4 is to 6 as 3 is to 7, there 35 is no difference in voltage between the points 29 and 30. Further, it will appear that the diaphragm can be made of such a weight that the first impact of sound will carry it over to one side and unbalance the 40 terminals and keep them unbalanced, the diaphragm continuing to operate, causing vibrations in the line but not passing through zero. The voltage on the line which is connected permanently to the normally neutral points will be above zero during the vibrations. It may be noted in this 45 connection that by permanent connection is meant that the connection is not to such a variable member as the member 5.

50 What I claim as my invention is:

1. In an electrical system, a plurality of units consisting each of a Wheatstone bridge having battery permanently connected at the juncture of two of the arms and 55 terminating at the juncture of the other two arms in a movable element, a separate source of wave energy for each element in each unit for operating the element associated therewith to disturb the potential at the other two junctures of the other two arms in each unit, said bridges connected in 60 series.

2. In an electrical system, a unit having 65 a multiple circuit, a battery bridged across the sides of said multiple circuit dividing

the multiple circuit into two divisions, a point in each division at the point of juncture of the two branches of the multiple, said points normally of the same potential, a plurality of such units, a main circuit, 70 said units permanently connected in series in the main circuit using said points of normal potential as terminals, the battery in each unit terminating in a permanent connection on one side of the bridge and terminating in the other side in a movable element operable by wave energy to disturb the balance of the voltage at said points of juncture, each unit thereby impressing corresponding potential variations to the main 80 circuit, thereby producing a variation in the main circuit equal to the algebraic sum of the individual variations of the units.

3. In an electrical system, a unit having a multiple circuit, a battery bridged across the sides of said multiple circuit dividing the multiple circuit into two divisions, a point in each division at the point of juncture of the two branches of the multiple, said point normally of the same potential, 85 a plurality of such units in one group, a plurality of such groups, a main circuit, said units connected in series in said main circuit using said points of normal potential as terminals, one terminal of the battery in each unit terminating in a movable element operable by wave energy to disturb the balance of the voltage at the said points of juncture, each unit thereby impressing the corresponding potential variations on the main circuit, a separate source of wave energy for each group of units for affecting 95 all of the variable elements similarly, thereby impressing upon the main circuit the arithmetic sum of all the variations in the group and the several groups impressing upon the main circuit the algebraic sum of the variations produced by each group.

4. In an electrical system, a plurality of units consisting each of a Wheatstone bridge having battery connected at the juncture of two of the arms and terminating at the juncture of the other two arms in a movable element, a separate source of wave energy for each element in each unit for 105 operating the element associated therewith to disturb the potential at the other two junctures of the other two arms in each unit, a main circuit terminating at said terminals and an electrical reproducer or repeater on 110 said line for receiving and responding to the algebraic sum of said variations.

5. In an electrical system, a unit having a multiple circuit, a battery bridged across the sides of said multiple circuit dividing 115 the multiple circuit into two divisions, a point in each division at the point of juncture of the two branches of the multiple, said points normally of the same potential, a plurality of such units, a main circuit, 120

5 said units connected in series in the main circuit using said points of normal potential as terminals, the battery in each unit terminating in a connection on one side of the bridge and terminating in the other side in a movable element operable by wave energy to disturb the balance of the voltage at said points of juncture, each unit thereby impressing corresponding potential variations 10 to the main circuit, thereby producing a variation in the main circuit equal to the algebraic sum of the individual variations of the units, and an electrical reproducer or repeater on said line for receiving and responding to said variations.

6. In an electrical system, a unit having a multiple circuit, a battery bridged across the sides of said multiple circuit dividing the multiple circuit into two divisions, a 20 point in each division at the point of juncture of the two branches of the multiple, said point normally of the same potential, a plurality of such units in one group, a plurality of such groups, a main circuit, said 25 units connected in series in said main circuit using said points of normal potential as terminals, the battery in each unit terminating in a connection on one side of the bridge and terminating in the other side in a movable element operable by wave of energy to disturb the balance of the voltage at the said points of juncture, each unit thereby impressing the corresponding potential variations on the main circuit, a separate 30 source of wave energy for each group of units for affecting all of the variable elements similarly, thereby impressing upon the main circuit the arithmetic sum of all the variations in the group and the several 35 groups impressing upon the main circuit the algebraic sum of the variations produced by each group, and an electrical reproducer or repeater on said line for receiving and responding to said variations.

45 7. In an electrical system a unit consisting of a Wheatstone bridge having the battery connected at the juncture of two of the arms and terminating at the juncture of the other two arms in a movable element, a plurality 50 of such units in a group, a plurality of such groups, a main circuit, said units connected in series in said main circuit, using the remaining juncture points of the arms as terminals, a separate source of wave energy 55 for each group of units for affecting all the variable elements similarly, thereby impressing upon the main circuit the arithmetic sum of all the variations in the group and the several groups impressing upon the main 60 circuit the algebraic sum of the variations produced by the separate groups.

8. In an electrical system a unit consisting of a Wheatstone bridge having the battery connected at the juncture of two of the 65 arms and terminating at the juncture of the

other two arms in a movable element, a plurality of such units in a group, a plurality of such groups, a main circuit, said units connected in series in said main circuit, using the remaining juncture points of the arms as terminals, a separate source of wave energy for each group of units for affecting all the variable elements similarly, thereby impressing upon the main circuit the arithmetic sum of all the variations in the group and the several groups impressing upon the main circuit the algebraic sum of the variations produced by the separate groups, and an electrical reproducer or repeater on said line for receiving and responding to the 70 algebraic sum of said variations.

9. In an electrical system a unit comprising a circuit with a battery and terminals, said battery connected in a balanced condition to deliver normally no voltage at said terminals, one of the terminals of said battery terminating in a sound movable element so adjusted that the sound waves in moving said element produce at said terminals corresponding potential variations, a 80 plurality of such units, a main circuit, said units connected in series in said circuit, thereby impressing in the circuit resultant variations from all said units, a second main circuit, a source of electric energy in said 85 circuit, said first and second circuits located within the influence of each other so that the variations in the first circuit affect the energy in the second main circuit.

10. In an electrical system a unit comprising a circuit with a battery and terminals, said battery connected in a balanced condition to deliver normally no voltage at said terminals, one of the terminals of said battery terminating in a sound movable element so adjusted that the sound waves in moving said element produce at said terminals corresponding potential variations, above and below the point of zero voltage, a 100 plurality of such units, a main circuit, said units connected in series in said circuit, thereby impressing in the circuit resultant variations from all said units, a second main circuit, a source of electric energy in said 105 circuit, said first and second circuits located within the influence of each other so that the variations in the first circuit affect the energy in the second main circuit.

11. In an electrical system a unit comprising a circuit with a battery and terminals, said battery connected in a balanced condition to deliver normally no voltage at said terminals, one of the terminals of said battery terminating in a sound movable element so adjusted that the sound waves in moving said element produce at said terminals corresponding potential variations, a plurality of such units, a main circuit, said units connected in series in said circuit, thereby impressing in the circuit resultant variations 115 120 125 130

of all said units, a second main circuit, a source of electric energy in said circuit, said first and second circuits located within the influence of each other so that the variations in the first circuit affect the energy in the second main circuit, a third circuit electrically related to the second circuit to receive energy from the second, said third circuit affected due to the relation of the three main circuits by the variations in the first main circuit.

12. In an electrical system a unit comprising a circuit with a battery and terminals, said battery connected in a balanced condition to deliver normally in voltage at said terminals, one of the terminals of said battery terminating in a sound movable element so adjusted that the sound waves in moving said element produce at said terminals corresponding potential variations, above and below the point of zero voltage, a plurality of such units, a main circuit, said units connected in series in said circuit, thereby impressing in the circuit resultant variations of all said units, a second main circuit, a source of electric energy in said circuit, said first and second circuits located within the influence of each other so that the variations in the first circuit affect the energy in the second main circuit, a third circuit, electrically related to the second circuit to receive energy from the second, said third circuit affected due to the relation of the third main circuit by the variations in the first main circuit.

13. In an electrical system a unit comprising a circuit, a battery and terminals, said battery connected in a balanced condition to deliver normally no voltage at said terminals, one of the terminals of said battery terminating in a sound movable element so adjusted that the sound waves in moving said element produce at said terminals corresponding potential variations, a plurality of such units, a main circuit, said units connected in series in said circuit, thereby impressing in the circuit resultant variations of all said units, a transmission circuit for wireless transmission of energy, said line associated with said transmission circuit and influenced thereby for the wireless transmission of the variations corresponding to the variations in said line circuit.

14. In an electrical system, a plurality of units consisting each of a Wheatstone bridge having battery connected at the juncture of two of the arms and terminating at the juncture of the other two arms in a movable element, a separate source of wave energy for each element in each unit for operating the element associated therewith to disturb the potential at the other two junctures of the other two arms in each unit, a main circuit terminating at said terminals and an electrical reproducer or repeater on said line for

receiving and responding to the algebraic sum of said variations, and a receiver responsive to said reproducer.

15. In an electrical system, a main circuit, a plurality of Wheatstone bridges connected across said circuit in series, a microphone in one of the limbs of each Wheatstone bridge, a separate source of current for supplying each Wheatstone bridge, and an electrical instrument in said main circuit responsive to the combined action of all of said microphones.

16. In an electrical system, a main circuit, a plurality of Wheatstone bridges connected in series across said circuit, a plurality of microphones for each Wheatstone bridge inserted in the limbs thereof, a separate source of current supply for each bridge, and an electrical instrument for said line responsive to all of said microphones.

17. In an electrical system, a main circuit, a plurality of Wheatstone bridges connected in series across said circuit, a differential microphone connected in the limbs of each bridge, a separate source of current supply for each bridge, and an electrical instrument for said line responsive to all of said microphones.

18. In an electrical system, a main circuit, a plurality of Wheatstone bridges connected across said circuit in series, a microphone in one of the limbs of each Wheatstone bridge, a source of current for supplying the bridges, an electrical instrument in said main circuit responsive to the combined action of all of said microphones.

19. In an electrical system, a main circuit, a plurality of Wheatstone bridges connected across said circuit in series, a microphone in one of the limbs of each Wheatstone bridge, a separate source of current for supplying each Wheatstone bridge, a repeater in said main circuit responsive to the combined action of all of said microphones.

20. In an electrical system, a main circuit, a plurality of Wheatstone bridges connected across said circuit in series, a microphone in one of the limbs of each Wheatstone bridge, a source of current for supplying the bridges, a repeater in said main circuit responsive to the combined action of all of said microphones.

21. In an electrical system, a main circuit, a plurality of Wheatstone bridges connected in series across said circuit, a plurality of microphones for each Wheatstone bridge inserted in the limbs thereof, a source of current for supplying the bridges, and an electrical instrument for said line responsive to all of said microphones.

22. In an electrical system, a main circuit, a plurality of Wheatstone bridges connected in series across said circuit, a plurality of microphones for each Wheatstone bridge inserted in the limbs thereof, a separate source

of current supply for each bridge, and a repeater for said line responsive to all of said microphones.

23. In an electrical system, a main circuit, a plurality of Wheatstone bridges connected in series across said circuit, a plurality of microphones for each Wheatstone bridge inserted in the limbs thereof, a source of current for supplying the bridges, and a repeater for said line responsive to all of said microphones.

24. In an electrical system, a main circuit, a plurality of Wheatstone bridges connected in series across said circuit, a differential microphone connected in the limbs of each bridge, a source of current for supplying the bridges, and an electrical instrument for said line responsive to all of said microphones.

25. In an electrical system, a main circuit,

a plurality of Wheatstone bridges connected in series across said circuit, a differential microphone connected in the limbs of each bridge, a separate section of current supply for each bridge, and a repeater for said line responsive to all of said microphones.

26. In an electrical system, a main circuit, a plurality of Wheatstone bridges connected in series across said circuit, a differential microphone connected in the limbs of each bridge, a source of current for supplying the bridges, and a repeater for said line responsive to all of said microphones.

Signed by me at Chicago, Illinois, this 20th day of February, 1914.
